UNITED STATES PATENT OFFICE.

WILLIAM W. CROCKER, OF SOMERVILLE, MASSACHUSETTS.

GLAZING-STRIP.

1,156,981.

Specification of Letters Patent.

Patented Oct. 19, 1915.

Application filed October 3, 1913. Serial No. 793,091.

To all whom it may concern:

Be it known that I, WILLIAM W. CROCKER, a citizen of the United States, residing at Somerville, county of Middlesex, State of Massachusetts, have invented an Improvement in Glazing-Strips, of which the following description, in connection with the accompanying drawing, is a specification, like characters on the drawing representing like parts.

In the construction of glass houses, skylights and similar structures it is customary to employ metal glazing strips shaped to be rigidly secured to the sash bars and provided with clamping means to retain the glass with sufficient force to prevent rattling while permitting contraction and expansion due to changes in temperature. The use of such glazing strips facilitates construction by making it unnecessary to provide specially shaped sash bars thereby cheapening and improving the method of construction.

The object of this invention is to provide a glazing strip of this general character but of a new and improved type.

The novel features of the invention will be fully described in the following specification and accompanying drawing and particularly pointed out in the claims.

Referring to the drawing in which I have illustrated a preferred form of my invention; the figure is a perspective view partly in section of my improved glazing strip applied to a sash bar.

Referring to the drawing in detail the sash bar is represented at 1 as constructed of T iron of usual shape. A glazing strip is provided for holding the glass in position relative to the sash bar comprising a glass-supporting member 2 and a retaining member 3, bolts 4 serving to secure these members together.

In accordance with my invention the glass-supporting member 2 is made from a strip of sheet metal the central portion being in the form of an inverted channel as shown at 5 providing a space for the heads of the bolts 4 and presenting an elevated glass-receiving surface as indicated at 6.

This glass-receiving surface is made sufficiently wide to provide for the contraction and expansion due to changes in temperature and to allow for irregularities in the size of the glass. Putty or equivalent material is preferably placed between the glass-receiving surface 6 and the glass as indi-

cated at 7. Laterally of this central portion the strip is shaped to provide gutters 8 which collect and carry off the water of condensation. The extreme edges of the strip are bent to embrace the top flanges of the T iron as indicated at 9.

The retaining member 3 is also made from a strip of sheet metal and is preferably of inverted channel shape as indicated at 10 having its lateral portions 11 extending horizontally from the central channel portion with the edges bent downwardly to engage the glass as indicated at 12. Thus a longitudinally rigid member is provided 70 having resilient glass-engaging edges which hold the glass in position with sufficient firmness to prevent rattling while at the same time permitting the movements of contraction and expansion caused by changes 75 of temperature.

By this construction I provide a glazing strip the parts of which can be cheaply manufactured from sheet metal and easily applied to sash bars made from ordinary 80 commercial structural iron such for instance, as T-iron. The glass is firmly, adjustably and positively clamped but can be easily removed and replaced by loosening the clamping bolts.

The channel shape of the glass-supporting member provides space for bolt heads making it possible to use this simple and efficient method of adjustably and pivotally securing the retaining member to the glass supporting member, without boring or tapping the sash bar. The sash bar illustrated is constructed to supply all the strength necessary and is of a shape which can be easily and cheaply obtained in the market. The parts 95 of the glazing strip are such as may be easily formed from sheet metal by simple and well known processes.

Having fully described my invention what I claim as new and desire to secure by 100 Letters Patent is:

1. In a device of the character described, the combination with a T-shaped sash bar, of a combined glass-supporting and gutter-forming member mounted thereon and consisting of a single strip of sheet metal bent to present two parallel gutters which rest on the upper surface of the sash bar, the portion of said strip between the gutters being elevated from the top of the sash bar 110 and presenting a flat glass-receiving surface, each of the outer edges of said strip

being bent downwardly and then inwardly underneath the edges of the sash bar thereby to embrace said edges, a retaining member situated above the glass-supporting member and constructed to clamp the glass against the glass-receiving surface, and bolts extending through said retaining member and the glass-receiving portion of the glass-supporting member to hold the retaining member in position.

2. In a device of the character described, the combination with a T-shaped sash bar, of a combined glass-supporting and gutter-forming member mounted thereon and consisting of a single strip of sheet metal bent to present two parallel gutters which rest on the upper surface of the sash bar, the portion of said strip between the gutters being elevated from the top of the sash bar and presenting a flat glass-receiving surface, each of the outer edges of said strip being bent downwardly and then inwardly underneath the edges of the sash bar thereby to embrace said edges, a retaining member situated above the glass-supporting member and presenting a channel-shaped body portion and laterally-extending wings at the edge of the bottom portion, the edges of the wings being bent downwardly to constitute resilient glass-engaging edges, and bolts ex-

tending upwardly through the glass-receiving surface and through the channel-shaped portion of the retaining member to hold the latter in position.

3. In a device of the character described, in combination, a T-shaped sash bar, a glass-supporting member mounted thereon, consisting of a single strip of sheet metal so bent that its central portion provides an elevated flat glass-receiving surface with gutters at each side thereof, the edges being bent to embrace the flanges of the T-shaped sash bar to secure the strip thereto, a retaining member consisting of a single strip of sheet metal, its central portion being shaped to form an inverted channel, its lateral portions extending laterally with downwardly turned edges to provide flexible portions to yieldably engage the glass to hold it in place against the glass-supporting member and bolts to connect the retaining member to the glass-supporting member.

In testimony whereof, I have signed my name to this specification, in the presence of two subscribing witnesses.

WILLIAM W. CROCKER.
